UNITED STATES PATENT OFFICE.

SIMON W. WARDWELL, OF PROVIDENCE, RHODE ISLAND.

WINDING-MACHINE.

SPECIFICATION forming part of Letters Patent No. 760,669, dated May 24, 1904.

Application filed September 16, 1903. Serial No. 173,455. (No model.)

To all whom it may concern:

Be it known that I, SIMON W. WARDWELL, a citizen of the United States, residing at Providence, in the county of Providence and State of Rhode Island, have invented certain new and useful Improvements in Winding-Machines, of which the following is a specification.

My invention relates to improvements in winding-machines, and especially to machines for winding from rotating supplies, such as spools, bobbins, and the like.

My invention comprehends improved devices for controlling the winding mechanism and also the delivery of the material wound from its supply.

The accompanying specification and drawings show my invention adapted for and applied to the production of magnet-coils or bobbins wound by what is known to the textile trade as the "universal" system of winding.

Figure 1 is a front view of a winding-machine of usual form with my improvements applied; Fig. 2, a front view of the devices for controlling the unwinding of the supply; Fig. 3, a side view of the same; Fig. 4, a sectional plan view on the line A A of Fig. 1, showing the devices for controlling the winding; Fig. 5, a side view of the inertia-wheel looking in the direction indicated by the arrow B, Fig. 4; Fig. 6, a view looking in the same direction, showing the method of supporting the inertia-wheel. Fig. 7 shows a modification of the traverse-guide; Fig. 8, a plan view of a detail of the same.

The purpose of my invention is, primarily, to so control the winding mechanism and the delivery of the material wound from a rotating supply that a material like insulated wire may be effectively wound without abrading the insulation and with such uniform tension that the coils of the package shall be laid with greater precision than is usual and that packages of the same length and wound with the same number of coils may not vary materially in diameter, a condition of importance in producing magnet-bobbins.

The winding-machine employed is in most respects similar to that described in my Patent No. 740,958, dated October 6, 1903, com-

prising a rotating winding-spindle *a* and a reciprocating traverse-guide *b*. The means whereby the relation of the winding-spindle's rotative speed and of the guide's reciprocation is adjusted and controlled are old, and therefore not here illustrated; but certain improvements in the structure and operation of the traverse-guide and spindle will be hereinafter described.

Secured to the frame of the winding-machine in a suitable manner are two rods *c*, only one of which is shown in the drawings, on which is mounted the bracket *d*, which supports a rotative supply device and its controlling mechanism.

The principle of operation of the device is the same as that disclosed in my Patent No. 740,958, dated October 6, 1903; but certain structural modifications embracing improvements will now be specifically set forth.

A bobbin-spindle *e* rotates in suitable bearings in the bracket *d* and is provided with conical washers, one fast and the other adjustable, to engage the spool and center it upon the spindle. Secured to the spindle is a brake-wheel *f*, (shown in the drawing as formed on the fixed conical washer,) through which the rotation of the supply is controlled. A brake-shoe *g*, adapted to bear upon the periphery of the brake-wheel, is carried at the end of an arm *h*, pivoted at *i* on the bracket *d*. A lever *j* is fulcrumed at its lower extremity on a rock-shaft *k*, having bearings in suitable lugs on the bracket *d*. (See Fig. 3.) At the top of the lever *j* is formed a lug *l*. A threaded pin *m* is adapted to slide in a bearing in the lug and is prevented from turning by a pin *n*, projecting from the lug into a groove or keyway in the pin *m*. Fastened to the lower end of the pin *m* is a spiral spring *o*, connected at its opposite end to the lower extremity of the arm *h*. A suitable finger-nut *p* fits the thread of the pin *m* and bears upon the lug *l*. By turning the nut the pin *m* is adjusted up or down, and thereby the tension of the spring *o* may be regulated. Pivoted at *q* is a bell-crank lever *r*, provided with a pin *s* at the extremity of its lower arm. The pin *s* engages a slot in an extension *t* of the lever *j*, which is preferably made of wire bent

in a curved form, as indicated, and secured to the lever *j* by its ends driven into holes in said lever. (See Fig. 3.) Through connections that will be described below the bell-5 crank lever *r* is shifted in position by any variation in tension of the material, and the pin *s* swings the lever *j* about its fulcrum, causing a change in the direction of action of the spring *o* relative to the pin *i*, on which the 10 brake-arm *h* is fulcrumed, and a corresponding change in the degree of said action. It is obviously desirable that the spring action shall decrease more rapidly as the tension of delivery of the material increases, and therefore 15 15 fore the slotted extension *t* is made of curved form, so that engaging as a cam with the pin *s* a more rapid movement of the lever *j* shall be effected as the pin *s* moves upward. Were the slotted extension *t* straight, the lever *j* 20 would obviously be moved as the pin *s* rises with a retarded motion, according to the well-known mechanical law governing crank action.

Referring to the action of the spring *o* upon 25 the brake *g*, the leverage with which the spring acts on the brake is measured by the perpendicular distance of the brake's fulcrum *i* to the line of action of the spring. Therefore were the lever *j* so shifted that the spring *o* 30 acted in a line passing through the axis of the fulcrum *i* no effect would be produced on the brake; but were it shifted to a position at right angles to that above defined it would act upon the brake with maximum effect.

35 As the spring *o* acts at all times on the arm *h* in a line passing through the axis of the lever *j*, it suffers no change in length because of change of position, and therefore the lever *j* can be shifted with practically no resistance 40 to such movement.

At the top of the bracket *d* is pivoted a second bell-crank lever *u*, one arm of which is formed of a rod or wire, one portion of which, bent at right angles to the arm and passing 45 through bearings in the bracket *d*, serves as a fulcrum for the bell-crank lever *u*. The other arm of the lever *u* is a conical sector *v*, fastened to the fulcrum portion of the rod and having concentric grooves *w w*, &c., adapted 50 to receive a cord *x*, fastened at *y* on the sector and connected at the other end to a long spiral spring *z*, anchored to the machine-frame. The effect of the pull of the spring *z* on the lever *u* may be varied by adjusting the 55 cord in the different grooves *w w* to change its leverage on the sector *v*. Further, the tension of the spring *z* may be adjusted by a novel means included in its anchorage device. (See Fig. 1.)

60 A cord *2*, fastened to the lower end of the spring *z*, passes around a sheave *3*, which is locked from rotation by the nut *4*, the latter having a handle *5*, whereby it may be readily tightened or loosened, as desired. At the lower 65 end of the cord is secured the weight *6*, which

serves to maintain the spring *z* at whatever tension to which it may be adjusted. The cord *2* passes once around the sheave *3*, is drawn constrictively upon the latter by the combined action of the spring *z* and the weight 70 *6*, and with the weight and spring adjusted in correct relation the friction due to this constriction suffices to resist the pull of either the weight or the spring when the sheave is locked from rotation.

To adjust the tension of the spring *z*, it is only necessary to lengthen or shorten it, according as more or less tension is required, and this is accomplished by loosening the nut 80 *4* and turning the sheave *3* to pay out or take up the cord leading to the spring.

At the opposite end of the lever *u* from the sector *v* is mounted a grooved pulley *7*, over which the wire from the supply-spool leads on its way to the thread-guide *b*. The pull of the wire acts against the tension of the spring *z* to vary the position of the lever *u*, and the movement of the latter is communicated to the lever *r* through a connecting-link *8*. A link *9* connects the lever *r* to a dog *10*, mounted on the detent-lever *11* of the winding-machine. The downward movement of the dog *10* carries its extremity into engagement with a disk *12* on the winding-spindle, thereby forcing the detent-lever *11* outward to release the 95 starting-lever and allow the stopping mechanism to act in a manner well-known to those familiar with this class of machines.

Pendent from an extension of the lever *u* 100 is a detector *13*, formed of wire with a hook-shaped loop extremity having an opening to receive the material. The width of the opening is just sufficient for the wire to pass through, and when a knot or tangle occurs it 105 engages the detector *13*, deflects the lever *u*, and through the connections before described operates to stop the winding. When the tension on the wire is released, through breakage or at the finish of the winding, the spring *z*, acting 110 on the sector *v*, draws it downward with considerable force, and to relieve the shock 115 provide a buffer-spring *14*, fastened to the bracket *d*.

My invention also includes novel means for 120 operating the machine by hand, a novel arrangement of inertia-wheel for controlling the winding-spindle, and a novel traverse-guide especially adapted for insulated wire.

The winding-spindle *a*, Fig. 4, is driven through the friction-pulley *15*, loose on the 125 spindle, but engaging the latter through the clutch member *16*, which when released by the operator is pressed into contact with the pulley by a saucer-shaped spring *17*. Carried on the clutch member *16* or formed integral therewith is a bevel-gear *18*, which meshes with a pinion *19* on the shaft *20*. This latter shaft *20* is mounted in a bracket *21*, pivotally supported from the top of the winding-machine on a rod *22*. (See Figs. 1 and 6.) 130

The clutch member 16 slides on the spindle *a* and is held from rotation by pins 23 23, projecting from a collar 24, fast on the spindle. Rotatable on the hub of the clutch is a collar 25, having a projection 26 engaging an opening 27 in a plate 28, fastened at the end of the bracket 21. It will be seen that as the clutch 16 slides on the spindle the bracket 21, through the connections above described, is 5 swung on its pivot-rod 22 to keep the pinion 19 always in mesh with its gear 18. The bracket 21 and plate 28 serve to cover the pinion 19 and protect it from dust, being cut away only sufficiently to expose that portion 10 of the pinion engaging the gear 18.

Mounted at the end of the shaft 20 is a hub 29, pinned to the shaft and serving as a bearing for the inertia-wheel 30. The wheel 30 is free to rotate ahead of the shaft, but is engaged to be driven thereby through a suitable clutch device. I prefer to employ the well-known mechanism illustrated in Fig. 5, in which a series of rolls 31 31 are mounted in pockets having inclined or eccentric faces, 20 which on the turning of the hub 29 force the rolls outward to impinge the inner surface of the hub of the inertia-wheel.

The end of the shaft 20 is of smaller diameter than its body, and on this reduced portion is mounted the crank 32. Projecting from the hub of the crank are two small pins 33 33, adapted to engage corresponding holes in the end of the hub 29. The hub of the crank has end play between the end of the 35 hub 29 and the limiting-washer 34, fastened to the end of the shaft, so that it can be readily engaged with or disengaged from the hub 29. To keep the crank normally out of engagement with the hub 29, a light spiral spring 35 40 may be interposed between the said hub and the hub of the crank. By this means the crank is prevented from rotating with the inertia-wheel, and the liability of injury to the operator is avoided.

In winding magnet-coils it is important that the insulation on the wire shall not be abraded or disturbed, and for this reason the traversing guide must be particularly resili- 45 ent and yielding to pass over any irregularity 50 on the surface of the coil without material resistance. At the points where one coil crosses another the wire rises up over the under coil, and the guide must be adapted to quickly respond to such sharp bends without pressing too hard upon the wire. While the guide as ordi- 55 narily constructed can be carried out from the surface of the package by overcoming the resistance to the swinging of the guide-carrying or traverse frame 36, the inertia of the latter is too great to be quickly overcome, and before a relieving movement could be accomplished the wire would be crushed into the bobbin and its insulation injured. By hinging the 60 guide on the traverse-bar 37, by which it is 65 supported and reciprocated I adapt it to swing

independently of the traverse-frame. As shown in Fig. 1, two ears 38 are provided on the vertical member 39, and on these is pivoted the guide-holder 40, supporting the usual guide *b*. The member 39 extends upward to 70 form a bearing against the back of the frame 36 and is bent backward and looped around toward the guide-holder to form a spring element 41. The top of the guide-holder is bent over and provided with an opening into which 75 the end of the spring is hooked. The tension of the spring 41 is strong enough to normally resist the pressure of the growing package, tending to force the traverse-frame away 80 from the spindle; but when the guide crosses a raised coil on the bobbin the sudden pressure compresses the spring, forcing the guide outward to ride over the projection. The spring then returns the guide to the straight 85 surface of the bobbin and maintains it always in close contact with that part of the surface on which the new coil is being laid.

Figs. 7 and 8 illustrate another form of guide mechanism, in which a spiral spring 42 is employed. The member 39 is formed in a rectangular extension above the traverse-frame, and a pin 43 projects from the downturned portion. The spring 42 surrounds the pin and extending through an opening in the member bears on the guide-holder 40. The latter also has a projecting pin to hold the spring in position and is formed with two arms 44 44, (see Fig. 8,) straddling the member 39 and serving as a bearing thereon to steady the upper end of the guide-holder. 90 The arms have right-angled portions at their ends which contact with the downturned portion of the member 39 to limit the move- 95 of the guide-holder under the pressure of the spring. This upper bearing for the guide is 100 of particular advantage in eliminating side play and adapting the guide to lay the coils with extreme precision. To attain further 105 rigidity, the hinge-bearings at the bottom of the guide-holder are formed some distance 110 apart.

The operation of my invention is as follows: When starting the winding, if the reciprocating guide is on a portion of the spindle other than that at which the winding 115 should commence the winding devices are operated by hand by means of the crank 32 until the guide is brought to the correct starting position. The wire is drawn from the supply over the pulley 7 down through the guide 120 and suitably secured to the winding-spindle. In winding-magnets it is essential that the wire shall be laid uniformly throughout the bobbin. The first coils wound upon the tube or mandrel are peculiarly liable to slippage and 125 displacement, because wire lacks that elastic constrictive adhesion which causes a yarn to retain its position on the tube. The coils of wound wire tend to distend and loosen on the tube. Hence the liability to slippage. The 130

first coils are therefore carefully wound by hand by means of the crank 32. Then the machine is started by releasing the clutch member 16 and allowing it to engage the friction-pulley 15, which rotates at a uniform speed. The latter tends to immediately start the winding-spindle, but must first overcome the inertia of the wheel 30. As the starting of the wheel cannot be accomplished instantly, the clutch 16 slips in the friction-pulley 15; but the friction between the two members is sufficient to impart to the wheel a rotative impulse, then actual rotation, and gradual acceleration of rotation until its normal speed is attained. Owing to the previously-described character of the clutch device employed in connection with the inertia-wheel, it is not necessary in stopping the spindle *a* to overcome the impetus of said wheel; but the latter continues to rotate free of the spindle until its momentum is exhausted. When the winding is started, the pull on the material wound depresses the pulley 7, which through the medium of the connecting-link 8 shifts the lever *r*, which in turn shifts the lever *j* and relieves the pressure of the brake *g* on the controlling-wheel *f*. Should there be any tendency to unduly relieve the tension on the material wound, this will be counteracted by the spring *z*, which acts to promptly tighten any slack in the material and maintain the desired tension by controlling the action of the brake-shoe *g*. In case the tension increases beyond the control of the supply devices the excessive depression of the pulley 7 will through the links 8 and 9 cause the depression of the stopping-dog 10 and its engagement with the disk 12 on the winding-spindle *a* to stop the machine. In the same manner the engagement of a knot or kink with the detector 13 serves to depress the lever *u* to stop the winding.

My invention has been described as particularly applicable for magnet-winding; but one may readily see that it is likewise adapted for winding other materials, especially where great precision of winding is desired.

I do not limit myself to the precise form and arrangement of structure herein shown; but

50. What I do claim is—

1. The combination in a tension and supply controlling device of a rotating supply, a brake-wheel, a swinging brake, a spring to engage the brake with the brake-wheel, a lever to carry the spring, a second lever shifted by variations in the tension of the material being wound and connections between the two levers whereby such variations of tension cause an accelerated or retarded change in the 60. brake action by varying the direction of action of the spring.

2. The combination in a tension and supply controlling device of a rotating supply, a brake-wheel to control the rotation of the supply, a swinging brake, a spring rockable to

vary its direction of action and a lever to rock the spring, formed at one portion as a cam, a second lever shifted by fluctuations of tension of the material wound and so engaging the cam portion of the first lever as to acceleratedly diminish the brake action or retardedly reapply it as required. 70

3. The combination in a tension and supply controlling device, of a rotating supply, a brake-wheel, a brake, a spring to actuate the brake, a lever supporting the spring, adapted to be rocked to vary the direction of action of the spring relative to the direction of action of the brake, a second lever operated by the resistance to the delivery of the supply and a cam element whereby the levers engage so that uniform motion imparted to the second lever shifts the first lever to release the pressure on the brake with accelerated or retarded motion. 75

4. The combination in a winding-machine with a tension and supply controlling device, of means for varying the tension applied to the material according to the resistance to the delivery thereof, and devices whereby an excess of resistance serves not only to relieve the tension but to arrest the operation of the machine. 80

5. The combination in a winding-machine with a tension and supply controlling device 95 comprising a rotating supply, a brake to control the rotation of the supply, means for varying the intensity of the brake-pressure by varying the direction of action of the force applied to the brake, relative to the direction of action of the brake, and devices whereby excessive tendency to relieve the brake-pressure acts to effect the stopping of the machine. 100

6. The combination in a winding-machine with a tension and supply controlling device 105 comprising a rotating supply, a brake to control the rotation of the supply, a spring to actuate the brake, means for varying the degree of action of the spring by shifting the direction of its line of action, and devices controlling the stopping mechanism of the machine whereby continued action of the spring-controlling mechanism to relieve the pressure on the brake serves to stop the machine. 110

7. The combination in a winding-machine 115 with a tension and supply controlling device, comprising a rotating supply, a brake, a spring acting on the brake, a lever to change the direction of action of the spring, devices acted on by variations in delivery of the material 120 from the supply to shift the lever to release or apply the brake, and devices connecting the supply-controlling device with the machine whereby continued resistance to the delivery of the supply after the release of the 125 brake will act to arrest the operation of the machine.

8. The combination in a winding-machine 130 with a winding-spindle and traverse-guide, and starting and stopping devices for con-

- trolling the same, of a tension and supply controlling device comprising a rotating supply, a brake to control the rotation of the supply, a spring acting on the brake and rockable to vary its direction of action, a lever to rock the spring, a second lever shifted by fluctuations in the delivery of the material wound adapted to rock the first lever and a connection between the second lever and the stopping devices of the machine whereby abnormal movement of the lever to release the brake acts to arrest the winding.
9. The combination with the starting and stopping devices of a winding-machine, comprising means to cause the arrestment of the winding, a detent-lever to maintain said means normally inoperative and a dog on said lever, of a tension and supply controlling device with a rotating supply, a brake acting on the supply, a spring operating the brake, a lever to rock the spring to change its direction of action, a second lever controlled by the delivery of the material and engaging the first lever to rock it to relieve or apply the brake-pressure and a connection between the second lever and the dog whereby extreme movement of said lever shifts the dog to move the detent-lever and release the stopping devices of the machine.
10. The combination in a winding-machine with stopping devices and a tension and supply controlling device, of a rotating supply, a brake to control the rotation of the supply, means to operate said brake with varying pressure, a lever to regulate said means, a pulley on said lever over which the material passes, a detector pendent from the lever and having a looped extremity with an opening of just sufficient width for the material to pass through, and connections between the lever and the stopping devices of the machine whereby when a knot or kink engages the detector on the lever to shift the latter, such movement will cause the stopping of the machine.
11. The combination with a tension device comprising a rotating supply, means to resist the rotation of the supply, a lever regulating said means and controlled by the delivery of the material, a spring acting on said lever to oppose the pull of the material, of a device for anchoring one end of the spring to allow adjustment of the length of the latter to vary its tension, comprising a sheave, a cord fastened to the spring and passing once around the sheave, a weight on said cord and means to lock the sheave against rotation.
12. The combination in a winding-machine with a rotating spindle and a swinging guide-carrying frame movable to and from the spindle, of a traverse-bar reciprocating in said frame, a guide for the material, supported on said bar, and means on the bar to yieldingly press the guide toward the spindle independently of the movement of the guide-carrying frame.

13. The combination in a winding-machine with a rotating spindle and a swinging guide-carrying frame, of a traverse-bar reciprocating in said frame, a vertical member on the bar, a traverse-guide supported on said member and a spring, acting between the member and the guide to press the latter yieldingly toward the spindle independently of the pressure of the guide-carrying frame.
14. The combination in a winding-machine with a winding-spindle and a guide-carrying frame, of a reciprocating traverse-bar, a vertical member on said bar formed to serve as a bearing against the traverse-frame, a guide for the material, hinged to the bottom of the vertical member and having a sliding bearing at the top serving to support the guide laterally while allowing it to swing, and a spring to press the guide away from the member.
15. The combination in a winding-machine with a winding-spindle and a guide-carrying frame, of a traverse-bar reciprocating in the frame, a vertical member on said bar to serve as a bearing for the bar on the frame, and formed with ears adjacent its lower extremity, and a rectangular portion at its upper extremity, a pin projecting from the down-turned portion of said extremity, a guide-holder hinged on the ears and formed with two arms straddling the vertical member to serve as a bearing thereon, the ends of the arms having right-angle portions to contact with said member to limit the movement of the holder, and a spring surrounding the pin and extending through an opening in the vertical member to bear on the guide-holder.
16. The combination with a rotatable spindle, of a driving-pulley rotatable on the spindle, a clutch member non-rotatable on the spindle but adapted to slide into and out of engagement with the pulley, a bevel-gear fixed on the clutch, a pinion engaging said gear, a movable bearing for the pinion and means connecting the bearing with the clutch member whereby the pinion is moved with the clutch to keep it always in mesh with the gear.
17. The combination with a rotatable spindle of a driving-pulley rotatable on the spindle, a clutch member non-rotatable on the spindle but adapted to slide into and out of engagement with the pulley and carrying a bevel-gear, a pinion engaging said gear, a shaft on which the pinion is fixed, an inertia-wheel rotated by said shaft, a bracket supporting the shaft, and means connecting the bracket with the clutch member to move the former with the movement of the clutch member to keep the pinion always in engagement with the gear.
18. The combination with a rotatable spindle, of a driving member rotatable thereon and formed with a clutch-face, a clutch member non-rotatable on the spindle but slidable to engage the driving member, a bevel-gear on the clutch member, a shaft, a bearing to support

the shaft with its axis at right angles to that of the spindle, a pinion on the shaft engaging the gear, a crank to turn the shaft and means connecting the clutch member to the shaft-bearing whereby the latter is carried with said member to keep the pinion in mesh with its gear.

19. The combination with a rotatable spindle, of a driving member rotatable thereon, a clutch member non-rotatable but sliding on the spindle to engage the driving member, said clutch member formed with a hub and carrying a bevel-gear, a shaft, a pinion on the shaft, means to rotate the shaft manually, a swinging bracket having a bearing for the shaft and a collar rotatable on the hub of the clutch member, and formed with a projection engaging the bracket to swing the latter with the movement of the clutch member.
20. The combination in a winding-machine with a rotatable spindle, of a driving-pulley rotatable on the spindle, a clutch member rotatable with the spindle and adapted to slide thereon to engage the driving-pulley, said member having a hub, a collar rotatable on the hub, a bevel-gear on the member, a pinion engaging said gear, a shaft carrying the pinion, a hub, fast on the shaft and provided with clutch devices, an inertia-wheel rotatable on the hub ahead of the shaft but driven

thereby through the clutch devices, a crank rotatable on the shaft but adapted to engage the hub to rotate the shaft, a bracket having a bearing for the shaft and pivoted to swing to adapt the pinion to follow the movement 35 of the clutch member, a plate fastened to the bracket to protect the pinion and having an opening, and a pin projecting from the collar on the clutch member to engage the opening in the plate for the purpose and in the manner 40 substantially as described.

21. The combination with a rotatable spindle, of a driving member rotatable thereon and having a clutch-face, a clutch member engaging the spindle to rotate it and slidable to contact with the driving member, a shaft supported in a bearing with its axis at right angles to that of the spindle, means to drive the shaft from the spindle, an inertia-wheel on the shaft, and a crank normally rotatable on the 50 shaft but adapted to engage the latter for the purpose described.

In testimony whereof I have signed my name to this specification in the presence of two subscribing witnesses.
